UNITED STATES PATENT OFFICE.

AUGUST SUNDH, OF HASTINGS-UPON-HUDSON, NEW YORK, ASSIGNOR TO OTIS ELEVATOR COMPANY, A CORPORATION OF NEW JERSEY.

FLUID-MOTOR OR PUMP.

1,159,610.

Specification of Letters Patent.

Patented Nov. 9, 1915.

Application filed April 8, 1913. Serial No. 759,601.

To all whom it may concern:

Be it known that I, AUGUST SUNDH, a citizen of the United States, residing at Hastings-upon-Hudson, in the county of 5 Westchester and State of New York, have invented a new and useful Improvement in Fluid-Motors or Pumps, of which the following is a specification.

My invention relates to fluid motors or 10 pumps, and more particularly to such devices employing a plurality of reciprocating pistons or plungers.

An object of the invention is the provision 15 of a simple, practical and efficient fluid motor which requires a minimum amount of space and which develops great power.

Another object of the invention is the provision 20 of a fluid pressure motor or engine of the reciprocating type which will deliver its power with a substantially uniform torque at all speeds.

A further object of the invention is the provision 25 of a balanced multi-cylinder fluid pressure motor in which all friction losses are reduced to a minimum thereby making it possible to obtain an unusually high degree of efficiency.

A further object of the invention is the provision 30 of a valveless multi-cylinder motor of the reciprocating type which is made up of few parts, all of which are extremely rugged and of generous proportions, and which are easily accessible for inspection or repairs.

35 Other objects of the invention will appear hereinafter, the novel combinations of elements being pointed out in the appended claims.

Broadly speaking, a motor constructed according 40 to my invention comprises a plurality of units, each of which consists of a plurality of double-acting oscillating cylinders radially disposed about a common center, the cranks of each unit being connected to, or integral with, a common crank shaft, the angle of the cranks being such that the resultant torque or turning moment is substantially constant during a complete revolution of the crank shaft.

45 It will be conceded by those who are familiar with fluid pressure motors, that the reciprocating type of motor is for many reasons superior to those which do not use the reciprocating principle, among the latter

type may be mentioned those which use 55 gears, vanes, etc., which may be broadly classified as rotary motors. While the reciprocating motor, when well constructed, possesses high efficiency and a long and useful life, its valve action is usually complicated and liable to get out of order and the power it delivers is not uniform in that the torque continually varies with each changing position of the pistons. While for some few power purposes this changing torque is 60 of no great moment, there are many cases when a varying torque is not only objectionable but positively prohibitive. A good example of this latter case is found in a power 65 driven passenger elevator or hoist, particularly where the motor is operated at slow 70 rotary speeds. the varying torque of the motor effecting an intermittent motion of the elevator car which is very noticeable and objectionable.

75 In the drawings accompanying this specification, Figure 1 is a sectional elevation view through the center of one of the power units of a motor constructed according to my invention; Fig. 2 is a sectional view of the 80 motor taken at right angles to Fig. 1; Fig. 3 is a diagram showing the crank setting.

Like reference characters denote similar parts in all of the figures.

85 Referring to the drawings which represent a fluid pressure motor containing an embodiment of my invention in its preferred form, it will be seen that the motor comprises three similar units designated by the numerals 1, 2 and 3, and each unit consists 90 of a plurality of double acting cylinders whose pistons 4, 5, 6, 7 and 8 are connected to a common crank pin 9, secured to, or made integral with, a three-throw crank shaft 10. For purposes of illustration I have shown 95 three units of five cylinders each, but while these respective numbers of units and cylinders are best suited for the purpose, it is to be understood that under certain conditions I may use more or less units and cylinders 100 than those shown and by me preferred.

Since the units are similar to each other, a description of one of them will answer for all. Each cylinder comprises a circular disk such as 11, which is bored at right angles to 105 its axis so as to form a cylinder bore 12, in which the piston 4 is adapted to reciprocate. A piston rod 13 passes through a combined

stuffing box and piston guide 4, and is connected at one end to the piston 4, and at the other end to the crank pin 9, by means of a pair of split yokes 15, 15, (Fig. 2). The cylinder disk 11 is surrounded for the greater part of its circumference by a bushing 16, which is carried by a circular web 17 formed in the casing 18. A rectangular port 19 is cored in the disk 11, and leads from the upper end of the cylinder bore 12 to a point on the surface of the disk at substantially 90° from the axis of the cylinder bore. Stationary ports 20 and 22 are located in the web 17 and bushing 16 and are adapted alternately to register with the cylinder port 19 as the disk 11 oscillates. The port 20 communicates with a chamber 21 which is one of a series of interconnected chambers 21 in the casing, while the port 22 communicates with a chamber 23, which is, in like manner, one of a series of interconnected chambers 23. The lower end of the cylinder bore 12 is connected by a port 24 cored in the cylinder disk 11 and adapted alternately to register with the co-acting stationary ports 25, and 26, in the bushing and web 16; the said stationary ports leading into the chambers 21 and 23, respectively. The interconnected chambers 21 are adapted to receive fluid under pressure while the interconnected chambers 23 are utilized to carry off the exhaust from the working cylinders. At the stuffing box end of each cylinder is a small port 27 in the disk which communicates with one end of the cylinder bore, and a pocket 28 formed in the cylinder disk adjacent the bushing 16. A similar port 29 connects the port 24 with a similar pocket 30, the said pockets 28 and 30, being of equal dimensions and area, and symmetrically disposed on either side of the cylinder bore. These ports 27 and 29 are for the purpose of balancing the fluid pressure to which the cylinder disk is subjected and the manner in which this is done will be pointed out later in connection with the description of the operation.

Referring more particularly to Fig. 2, it will be seen that the casings 18 of the several units, together with the end plates 31 and 32 are firmly secured together by means of the through-bolts 33. The crank shaft 10 is supported at either end by the end plates 31 and 32 through the intermediary of the anti-friction ball bearings 34, 34. The crank shaft is further supported and stiffened by means of intermediate bearings comprising metal split disks 35, 35, which clamp on the intermediate shaft portions lying on either side of the crank pin 9. These split disks 35, 35, rotate with the crank shaft 10, and are supported by the vertical webs 37, 37, formed in the casing. Ball bearings, such as 36, 36, are interposed between the webs and disks 35 so as practically to eliminate all friction.

The chambers 21 and 23 are connected by the pipes 38 and 39 to a suitable source of supply and discharge, respectively.

While the crank angle is optional and may be 120° so as to obtain a perfect mechanical balance, in the majority of cases I prefer to arrange the cranks as shown in Fig. 3, in which two of the cranks are 24° apart while the third crank is removed or set at an angle of 168° from each of the other cranks. With this arrangement, the same turning moment or torque is obtained from the fifteen cylinders as would be obtained were all the cylinders radially arranged around a center and each piston were connected to operate on a common crank pin. While the torque of the motor with the cranks arranged as shown in Fig. 3, will be substantially uniform, the cranks will be somewhat out of mechanical balance, and, whereas this arrangement might induce a vibratory motion were the motors to be operated at very high speed, at normal or low speed the tendency toward vibration reduces itself to zero for all practical purposes, and may be neglected.

The operation of the motor herein described is as follows: Assuming that the pipe 38 (Fig. 2) is connected to a suitable source of fluid pressure supply, such as a pump, pressure tank, or steam boiler, and the pipe 39 is connected to a discharge tank or other exhaust, fluid immediately fills the intercommunicating chambers 21 and acting on the pistons rotates the crank shaft and whatever driven mechanism may be operatively connected thereto. The piston 4 of the middle unit is shown at the end of its stroke and the ports 19 and 24 are out of communication with all of the stationary ports such as 20, 22, 25 and 26. Assume further that the crank pin 9 be moved a trifle to the left or in a counterclockwise direction. The crank end of the piston rod 13 together with the cylinder disk 11 will follow the crank pin and in so doing will carry the port 19 into register with the port 20, and the cylinder port 24 into register with the port 26, so that the upper side of the piston 4 will be subjected to fluid pressure from the chamber 21, while the lower side of the piston will be open to the exhaust through the chamber 23. The pressure acting on top of the piston 4 will exert a turning effect on the crank shaft 10. As soon as the crank shaft has turned through 180° the piston 4 will have reached the end of its stroke and a further rotative movement of the shaft will rock or oscillate the cylinder disk 11 so that the ports 19 and 24 in the disk register with the stationary exhaust and supply ports 22 and 25 respectively. Fluid pressure now enters the opposite end of the cylinder bore 12 and drives the piston in a reverse or upward direction, the upper end of the cylinder bore being open through

the ports 19 and 22, to the exhaust. The operation of all of the other cylinders is similar to that just described, the arrangement of ports being such that a substantially constant torque is exerted by the various pistons upon their respective crank pins 9, 40 and 41, to effect a counter-clockwise rotation of the crank shaft 10.

When the chambers 21 are considered as pressure chambers, and the chambers 23 as exhaust chambers, the motor will rotate in an anti-clockwise direction, but by reversing these connections, so that the chambers 23 become pressure chambers and the chambers 21 become exhaust chambers, the motor will rotate in the opposite direction. This change over may be effected by means of a suitable valve exterior to the motor.

It will be observed that when pressure is acting upon the top of the piston 4, it is also acting upon the bushing 16, so that there is no pressure whatever tending to produce friction between the cylinder disk and the bushing 16 surrounding it. When pressure enters the port 24 and acts upon the lower surface of the piston, the pressure also acts upon the combined stuffing box and piston rod guide 14, tending to move it and the cylinder disk in a direction opposite to that of the piston and toward the crank shaft. It is the function of the pockets 28 and 30 in connection with the ports 27 and 29, respectively, to compensate for this pressure, and the pockets are of such size and so designed that this tendency is exactly counterbalanced. It is evident that when pressure is admitted to the lower end of the cylinder bore 12, this pressure finds its way through the ports 27 and 29, and into the pockets 28 and 30, respectively. As these pockets are similarly disposed about the axis of the cylinder bore regardless of the angularity of the crank shaft, any pressure introduced simultaneously into both pockets exerts a resultant pressure tending to carry the cylinder disk upwardly, the direction of said resultant pressure acting at all times along a line which coincides with the axis of the cylinder bore. By this arrangement I am enabled absolutely to balance each and every cylinder disk against fluid pressure, so that there will be practically no friction between the oscillating cylinders and their surrounding bushings regardless of fluid pressure conditions and speed.

It will be further observed that each piston exerts a driving force on a crank pin in a straight line, and, as the motor is perfectly balanced against fluid pressure, the efficiency will be unusually high. The exchange of ports from pressure to exhaust and vice versa, takes place just when the cranks pass the dead center for each cylinder, and this exchange provides a quick opening of the ports just at the time when

a minimum amount of fluid is taken in or discharged from the cylinders which is of substantial practical value, particularly where the motor fluid is of an incompressible nature such as water or oil, since it prevents any choking action due to a restricted flow of fluid.

A motor constructed according to my invention, using a plurality of oscillating cylinders, will develop great power in a very small space. The usual cam or eccentric operated valves, together with innumerable valve operating parts are entirely dispensed with. All crossheads and connecting rods are done away with, and the result is an extremely simple, compact and powerful motor, having a very small number of parts. Each part is sturdy and of simple design, and readily accessible for purposes of inspection or repair, and, owing to the almost entire absence of friction, the efficiency will be high and the life of the motor long.

While I have described my invention as operating as a motor, it is obvious that the same will operate as a pump when the crank shaft is driven by a suitable motor. All of the advantages of the invention being equally pronounced whether the same be operated as a motor or a pump.

It will be understood that while I have shown a motor or pump constructed according to a preferred form of my invention, I wish not to be limited to the precise construction and arrangement of parts herein set forth, since it is obvious that one skilled in the art could readily make various minor changes without departing from the spirit and scope of the invention.

What I claim, and desire to secure by Letters Patent of the United States is:—

1. A fluid pressure motor comprising a plurality of units, each unit consisting of a substantially circular casing provided with a plurality of radially disposed circular bores, each bore containing an oscillating disk cylinder, a pressure and exhaust chamber located between each circular bore, ports leading from said chambers to the disk cylinders, means for connecting said units together so that the exhaust and pressure chambers of one unit register with the corresponding exhaust and pressure chambers of the other units, and means for placing all of the exhaust chambers and the pressure chambers into communication with each other, respectively.

2. A fluid pressure motor comprising a plurality of units, each unit consisting of a substantially circular casing provided with a plurality of radially disposed circular bores, each bore containing an oscillating disk cylinder, a pressure and exhaust chamber located between each circular bore, ports leading from said chambers to the disk cylinders, means for connecting said units to-

- gether so that the exhaust and pressure chambers of one unit register with the corresponding exhaust and pressure chambers of the other units, and means comprising a 5 head or cover for the casing of one of the units for placing the corresponding exhaust and pressure chambers of all of the units in communication with each other, respectively.
- 10 3. A fluid pressure motor comprising a casing, a plurality of circular bores in said casing adapted to receive oscillating disk cylinders, pressure and exhaust chambers located between each circular bore, a casing 15 head adapted to place all of said pressure and exhaust chambers in communication with each other, respectively, and ports leading from a pressure chamber and from an exhaust chamber to adjacent cylinders.
- 20 4. A fluid pressure motor comprising a casing, a circular bore in the casing, a disk adapted to oscillate in said bore, a cylinder formed in the disk, pressure and exhaust chambers formed in said casing adjacent
- 25 said circular bore, a port leading from each chamber to the periphery of the cylinder disk, and a port in said disk adapted alternately to register with the ports of said pressure and exhaust chambers.
5. A fluid pressure motor comprising a 30 casing, a circular bore in the casing, a disk adapted to oscillate in said bore, a cylinder formed in the disk, pressure and exhaust chambers formed in said casing on either 35 side of said circular bore, ports leading from each chamber to the periphery of said cylinder disk, and ports in said disk adapted alternately to register with said chamber ports during the oscillation of the cylinder disk.

In testimony whereof, I have signed my name to this specification in the presence of two subscribing witnesses.

AUGUST SUNDH.
